Leontine Hayes,

WITNESS:

C. O. PLUMMER

INVENTOR

BY *Victor J. Evans*

ATTORNEY

UNITED STATES PATENT OFFICE.

CHARLES O. PLUMMER, OF GEARY, OKLAHOMA.

GATE FASTENER.

Application filed February 21, 1924. Serial No. 694,396.

To all whom it may concern:

Be it known that I, CHARLES O. PLUMMER, a citizen of the United States, residing at Geary, in the county of Blaine and State of Oklahoma, have invented new and useful Improvements in Gate Fasteners, of which the following is a specification.

My present invention has reference to a gate fastener, and my object is to produce a device for this purpose which shall be of a simple construction, cheaply manufactured and easily applied, and which will effectively hold a gate locked to a gate post.

A further object is the production of a gate fastener in the nature of a compound lever having a hook associated therewith to engage the end bar of a gate, the device being pivotally connected with a gate post and when swung to locking position will draw on the hook to hold the same rigid and thereby prevent the accidental unlocking of the gate.

To the attainment of the foregoing, reference is to be had to the drawing which accompanies and forms part of this application.

In the drawing:—

Figure 1 is a view of a gate locked to a gate post in accordance with this invention.

Figure 2 is a sectional view on the line 2—2 of Figure 1.

Figure 3 is a perspective view of the fastener.

In the drawing, the numeral 1 designates a swinging gate, and 2 the latch post therefor. On the post 2 there is swingably secured, as at 3, a substantially U-shaped yoke 4. This yoke has the ends of its arms bent to provide eyes that receive therethrough the comparatively straight inner end portions 5 of a lever 6. The lever is preferably constructed from a single piece of wire so that the body thereof is U-shaped in plan. The end portions 5 are bent inwardly and

extended to provide a central crank portion 45 7. This crank is also substantially U-shaped in plan but is arranged at an outward angle with respect to the body of the lever. The crank has swingably connected thereto the inner end of a rod 8, the outer end of which 50 being formed with a hook 9.

The hook 9, when the compound lever construction above described has the elements constituting the same swung to substantially parallelism, is designed to be arranged on 55 the vertical end bar of the gate 1. The joint between the sections comprising the compound lever is broken by the swinging of the lever proper on the yoke which, of course, draws the crank portion 7 of the 60 said lever inwardly or toward the latch post, and such movement also draws upon the hook to move the gate in the direction of the latch post. The latch cannot be accidentally unlocked, but the lever thereof 65 may be easily swung toward the gate to permit of the hook being detached from the gate stile. The improvement may be used in connection with the ordinary latching bail between the gate and gate post, if desired. 70

Having described the invention, I claim:—

In combination with a swinging gate and a latch post therefor, of a means for drawing the gate toward the latch post and for locking said gate thereto, said means comprising a yoke pivoted to the latch post, a lever whose body portion is substantially U-shaped in plan having inner inturned ends swingably connected to the ends of the yoke, the ends of the lever merging into a substantially 75 U-shaped crank portion disposed centrally of the lever proper and arranged at an angle with respect thereto, and a hook swingably connected with the crank portion of the lever, as and for the purpose set forth. 80 85

In testimony whereof I affix my signature.

CHARLES O. PLUMMER.
